Edward Socher of Newark, N. J.
Letters Patent No. 2372, Dated July 24, 1864.
Design for a Trade Mark.

The schedule referred to in the Letters Patent and making part of the same.

To all whom it may concern:

I, Edward Socher of the city of Newark in the County of Essex, and State of New Jersey, have originated a new Pattern or Design for a Trade Mark, of which the following is a full, clear and exact description, reference being had to the accompanying Specimen, or drawings making part of this Specification.

The Design of the Trademark consists of an ornamental shaped label bounded with white, and blue lines a, on the red ground b. Inside of the lines a, is drawn a dark line c, c, on each end of the oval d, d, within which the name of goods is lettered, such as "Hines' Superior Bag rummer", the latter words being changed according to the article contained in the package.

Above the oval d, d, to the left the quantity and to the right the number of the goods are marked while below the said oval on a circular dark spot a white star E, E, is printed on each side.

Within the inner oval, on the dark fine ground f, f, a medal shaped white ring is printed, within which on the blue ground g, g, the initials H, S, T, are placed. Above the medal is a flying blue shaded white ribbon h, h, with the words printed in blue, "Superior Quality".

The combination of colors represents the American Red, White and Blue.

This label or trade mark is placed on the outside of the packages in which the goods are contained.

What I claim as my invention and desire to secure by Letters Patent, is: The Design for the Trade Mark as described and shown

Witnessed,

Ernest Hennauer.

John Welfling.

W.D.

Edward Socher.
